UNITED STATES PATENT OFFICE

HOWARD T. CASEY AND CHARLES P. NOSER, OF ROCHESTER, NEW YORK, ASSIGNEES
TO THE SYMINGTON COMPANY, OF NEW YORK, N. Y., A CORPORATION OF MARY-
LAND

RETAINING DEVICE

Application filed January 3, 1927. Serial No. 158,658.

This invention relates to retaining devices and, more particularly, to such adapted for application to the ends of draft keys to prevent undesired removal or loss thereof.

5 The principal object of our invention, generally considered, is the provision of an improved key retainer adapted for application to one or both ends of draft keys for preventing undesired removal or loss thereof.

An object of our invention is the provision of a draft key retainer comprising a looped member adapted to fit over or encircle an end of an associated draft key, the upper or lower portion or both portions of said retainer being provided with lugs adapted to engage in a corresponding aperture or pocket in an associated key, said retainer being either forced over the end of the key until it snaps or springs into place or applied to the end 15 thereof and then contracted to cause the lugs to engage in the aperture or pocket in said key to hold the retainer in position.

Another object of our invention is the provision of a draft key retainer comprising an integral loop adapted to be forced over the end of an associated key and held in place by its own resiliency, said loop being provided with one or more lugs extending toward each other and adapted to engage in a corresponding aperture or pocket near the end of said 20 key.

A further object of our invention is the provision of a retaining device adapted for use with draft keys and comprising an integral looped member preferably tapered toward its ends and formed with one or more registering lugs adapted to engage in a corresponding pocket or aperture near the end of the key, the inner end of said lug or lugs being preferably bevelled to conform to the usual taper on the end of a draft key to facilitate application of said device.

Other objects and advantages of the 25 invention relating to the particular conforma-

tion and construction thereof will become apparent as the description proceeds.

Referring to the drawing illustrating our invention, the scope whereof is defined by the appended claims:

Figure 1 is a side elevation of draft rigging and a portion of a car underframe to which the same is applied, particularly showing draft rigging keys with retaining devices thereon embodying our invention.

Figure 2 is an elevational view of a retaining device embodying our invention detached from the associated key.

Figure 3 is a longitudinal sectional view of a key and associated retainer showing said 60 retainer partly applied to the key.

Figure 4 is a transverse sectional view of a key showing a retainer, such as illustrated in Figure 2, applied thereon.

Figure 5 is a longitudinal section view on 65 the line 5-5 of Figure 4.

Figure 6 is a plan view of the retainer shown in Figure 4 applied to an associated key.

Figure 7 is an elevational view of a slightly modified form of retainer embodying our invention.

Figure 8 is a longitudinal sectional view of a key showing a retainer, as illustrated in Figure 7, in full lines immediately upon application over the end of said key and in dot and dash lines after compression or contraction thereof to engage said key.

Although our invention is adapted for use 80 with draft keys or the like, generally, and for other purposes, and may be used with various kinds of draft rigging, we have for purposes of illustration shown in Figure 1 the invention employed with draft rigging of the Farlow two-key type. In said figure, a fragmentary portion of a car underframe is illustrated, draft or center sills 1 being shown with cheek plates 2 applied on the outer sides of the webs 3 thereof in accordance with usual practice. Said cheek plates 2 may be

connected to the sills by rivets or the like 4 and are preferably formed with flange portions 5 defining slots 6 and 7 therethrough, registering with correspondingly slotted portions in the webs 3 of the sills 1. Through the slots 6 and 7 extend draft keys 8 and 9, respectively, and said keys serve for connecting and supporting an associated coupler 10, horizontal yoke 11 and front follower 12. Cooperating with the front follower 12 and embraced between the arms of the yoke 11, any desired form of cushioning mechanism 31 is illustrated diagrammatically by dot and ~~dash lines~~.

15 The keys 8 and 9 may each comprise, if desired, a pointed or tapered end portion 14 and a head (not shown) on the opposite end thereof. Alternatively, said keys or one of them may be pointed or tapered at each end, if desired. The pointed or headless end or ends 14 of the key 8 or 9, or both, is formed with an aperture or pocket 15 preferably positioned at the usual distance from the end of the key for the application of a key retainer. A preferred embodiment of our improved form of key retainer comprises a member 16 preferably formed as an elongated or flattened loop adapted to fit over, or encircle if closed, the end of an associated key, as illustrated particularly in Figure 4. Said looped member 16 may conveniently be formed by casting although we do not wish to be limited to such construction. It is desirably formed angular or ribbed along the edges of the upper and lower portions thereof although this construction is not essential.

20 The upper or lower portions or both of said portions of the retainer 16 are formed with preferably integral bosses or lugs 17 extending inwardly or upwardly and downwardly, respectively, the inner ends of said bosses or lugs, in the embodiment illustrated in Figures 1 to 6, inclusive, being preferably bevelled or inclined as indicated at 18 to correspond with the tapering of the associated end of the key 8 or 9. The upper and lower portions of the retainer 16 may be normally so disposed that, in order to apply the retaining member to the key, it will be forced over the end thereof until the loop springs apart and permits the lugs 17 to snap into place, as illustrated in Figure 5, when the retainer reaches this position. Alternatively, the retainer may be normally formed with 25 the upper and lower portions disposed a somewhat greater distance apart so that, after application, it is desirable to apply force or pressure to contract or draw the upper and lower portions of the retainer toward one another and cause the lugs 17 thereof to more effectively engage in the aperture 15 in the associated key. In any event, as will be apparent, the resiliency of the loop prevents undesired removal or loss of the re-

tainer and so, likewise, of the key after assembly of the retainer and key, as illustrated.

30 Although we have shown the aperture or pocket 15 as extending entirely through the key, it is obvious that it need not be formed in this manner but may comprise merely a pocket for the lug or for each lug 17 as illustrated in Figure 8. The ends of the retainer 16 are shown as tapering although this is not essential. Such tapering, however, is desirable for increasing the resiliency of the device at the ends thereof and facilitating application and removal thereof. By tapering the ends, the wear on the retainer is substantially restricted to the central portion as is desirable. Although each lug is shown with an aperture 19 cored or otherwise formed therethrough, such a construction is not essential but desirable for keeping down the weight of the device.

35 In the embodiment illustrated in Figures 7 and 8, the upper and lower portions of the retainer 16^a may be similarly formed but more widely spaced than those of the first embodiment, although the inner ends of the lugs 17^a need not be bevelled or sloped because the retainer is normally so wide that the distance between the inner ends of said lugs corresponds with the thickness of the associated key 9. After application to the key, the retainer 16^a, shown in full lines in Figure 8, may be contracted or compressed, or the upper and lower portions forced, together, to the position shown in the dot and dash lines where the lugs 17^a thereof engage in the corresponding apertures or pockets 20 and 21 on the upper and lower sides, respectively, of the key 9. Although a plurality of pockets 20 and 21 are illustrated in this embodiment, it is obvious that instead an aperture corresponding to the aperture 15 of the first embodiment may be employed extending between the upper and lower surfaces of said key. Except as specifically described in connection with the embodiment illustrated in Figures 7 and 8, the construction thereof may correspond with that of the first embodiment.

40 When the retainer 16 or 16^a is assembled with the key 8 or 9, a limited amount of angling therebetween is permitted so that, upon angling of the key, the retainer will tend to remain parallel with the associated cheek plate and present a relatively large wearing area thereto, thereby minimizing wear between the parts. It will be apparent that the retainer is easily applied and removed and, on account of being formed as a unitary or integral device, there are no parts to lose and, on account of its relatively simple configuration, it may be readily cast and, therefore, manufactured at relatively small cost.

45 Having now described our invention, we claim:

1. A retainer adapted for use with draft keys comprising an integral closed resilient loop relatively wide at its central portion and tapered toward the ends thereof, said loop conforming approximately in inner dimensions with the end portion of a draft key, provided with a lug disposed intermediate the ends thereof, adapted to engage in a corresponding pocket in said key, and adapted to be forced over the end portion thereof and held in place by its own resiliency.
2. A retainer adapted for use with draft keys comprising an elongated resilient closed loop adapted to encircle an end portion of a key and formed with a lug intermediate the ends thereof adapted to engage and be resiliently held in a pocket near the end portion of the key for holding said retainer in place.
3. A retainer adapted for use with draft keys comprising a unitary member formed as an elongated loop adapted to fit an end portion of an associated key and formed with straight upper and lower portions each having outstanding ribs along the edges thereof and a curved end portion, said straight portions each having an inwardly extending lug rigid therewith and adapted to fit in a corresponding aperture near the end portion of said key.
4. In railway draft rigging, a draft key with an apertured end portion and a retainer comprising an elongated spring loop fitting around said end portion and having an inner lug disposed intermediate the ends of said retainer and fitting the aperture in said end portion, said loop being applied to the key by springing it over the end thereof until the lug snaps into place in the aperture of the key.
5. A retainer adapted for use with draft keys comprising an elongated closed spring loop, said retainer being formed with an integral inwardly extending lug adapted to be forced over an end portion of a key until it snaps into place in a corresponding aperture therein.
6. A device adapted for retaining an associated draft key in place comprising a continuous elongated spring loop having a rigid lug fitting an aperture near the end of a key, the inner end surface of said lug being beveled to facilitate application of the retainer.
7. A retainer comprising an elongated closed spring loop member formed with axially aligned rigid lugs adapted to fit in an aperture near an end of a railway draft key and adapted for application over the end portion of such a key with subsequent contraction thereof until the lugs engage in said aperture to hold the retainer in place.
8. In railway draft rigging, in combination, a draft key and a retainer thereon comprising an elongated integral closed resilient loop with rigid lugs fitting an apertured por-
- tion of said key and held therein by the resiliency of the retainer.
9. A retainer comprising an elongated loop member formed with a rigid lug adapted to fit in an aperture in an end portion of a flat railway draft key and adapted for application over said end portion of the key, and held in place by having the upper and lower portions thereof forced together until the lug engages in said aperture.
- In testimony whereof we affix our signatures.
